Fig. 5

FIG. 1 is a left front perspective view of the compass showing my new design in the open usage position.

FIG. 2 is a perspective view of the compass of FIG. 1 with the upper casing closed with respect to the lower casing.

FIG. 3 is a top plan view of FIG. 1.

FIG. 4 is a left side elevational view thereof.

FIG. 5 is a top plan view thereof with the sighting devices in their storage position.

FIG. 6 is a rear plan view of the compass with the upper casing closed with respect to the lower casing.

The bottom of the lower housing of the compass shown in the figures is a plain surface without ornamentation.

I claim:

The ornamental design for a digital display compass, substantially as shown and described.
